ATTORNEY

UNITED STATES PATENT OFFICE.

OTTO A. FREDERICKSON, OF WEATHERSFIELD, CONNECTICUT, ASSIGNOR TO THE AMERICAN WIREMOLD COMPANY, OF HARTFORD, CONNECTICUT, A CORPORATION OF CONNECTICUT.

CIRCULAR LOOM.

Application filed June 8, 1925. Serial No. 35,582.

To all whom it may concern:

Be it known that I, OTTO A. FREDERICKSON, a citizen of the United States, residing at Weathersfield, county of Hartford, and 5 State of Connecticut, have invented an Improvement in Circular Looms, of which the following description, in connection with the accompanying drawings, is a specification, like characters on the drawings representing like parts.

This invention relates to circular looms and more particularly to means for supporting and driving the shuttle or shuttles of a circular loom.

15 Various constructions have been proposed heretofore for supporting and driving the shuttle of a circular loom, but since the shuttle travels in a circular path thru the open shed, difficulty has been experienced in devising means that will support and drive the shuttle smoothly without pinching, deflecting or otherwise disturbing the threads of the open shed.

25 The driving means for the shuttle should be so constructed that it will maintain complete control of the shuttle to prevent the same from racing ahead when the speed of the loom is suddenly checked and the shuttle should be so supported that it will run smoothly about its path of travel with a minimum amount of friction.

30 One important feature of the present invention, therefore, relates to driving means for the shuttle comprising a disk that is advanced in the path of a circle about the axis of the loom and a cooperating bearing block which is secured to the shuttle and has a curved surface that partly embraces the disk so that the shuttle is driven and partly 35 supported by the disk. The disk preferably is notched and is positively rotated relative to the block at a speed that will cause the lower warp threads to enter the notches and pass between the block and disk without 40 being pinched or frayed.

45 Another important feature of the invention relates to a shoe or to shoes provided at the outer end of the shuttle to take the outward thrust of the shuttle due to centrifugal force, and since the cooperating driving disk and block serve to support the weight of the shuttle in addition to driving the same, the sliding shoe may serve to retain the shuttle in place upon the driving

55 disk without supporting the weight of the shuttle.

The sliding shoe or shoes of the present invention are particularly desirable when the shuttle travels within a fixed drum having vertical slots formed thru its wall for the 60 passage of warp threads. In this type of circular loom the shoe or shoes engages an annular bearing surface at the inner face of the drum and they will slide smoothly over the vertical slots without jarring the 65 shuttle.

70 It is found that the shoes of the present invention work extremely satisfactory when constructed of wood which has been soaked in oil, because when oil soaked wooden shoes are employed it is unnecessary to supply any lubricant to the annular bearing surface other than that supplied by the shoes, and any heating of the shoes by friction will 75 serve to drive out of the wood just enough oil to supply the needed lubricant. By using the oil soaked shoes all danger of excess oil accumulating upon the annular bearing surface and vertical slots intersecting said surface, where it is likely to soil the 80 warp threads, is avoided.

85 Other features of the invention and novel combination of parts in addition to the above will be hereinafter described in connection with the accompanying drawings which illustrate one good practical form of the invention.

80 In the drawings:—

90 Fig. 1 is a perspective view of a portion of a circular loom provided with means constructed in accordance with the present invention for supporting and driving the shuttle; and

95 Fig. 2 is a vertical sectional view thru the loom of Fig. 1;

100 The means of the present invention for supporting and driving the shuttle may be used in various different types of circular looms, and the construction of the loom shown is for the most part well known.

105 In the construction shown the loom frame is provided with a lower ring 10 having laterally extending lugs 11 adapted to rest upon a table or supporting bed 12, and the lugs may be secured to the supporting bed by bolts 13. Secured to the lower ring 10 of the frame are the uprights 14 positioned in spaced relation about the ring, and an in-

termidate portion of each upright 14 is secured to the ring 15 by bolts 16, while the upper ends of the uprights are secured to the upper ring 17 by bolts 18.

5 In the construction shown the circular loom is provided with a fixed drum 19 in which the shuttle or shuttles travel, and this drum is provided with a laterally extending flange 20 that is secured by bolts 21 to lugs 22 extending inwardly from the uprights 14. The fixed drum 19 is provided with a number of vertical slots 23 thru which the warp threads 24 extend to the weaving point. The various warp threads 24 are led from a creel (not shown) thru suitable tension means and then thru the lower guide eyes 25 upwardly to the upper guide eyes 26. The guide eyes 25 are shown as secured to a ring 27 supported by the uprights 14, while the guide eyes 26 are secured to the upper ring 17.

10 The warp threads 24 are shifted by heddles 28 to form the shed, as is usual, and the heddles 28 are mounted in bushings 29 within the flange 20 for vertical sliding movement, and each warp thread passes thru an eye 30 at the upper end of its heddle. The lower end of each heddle is provided with a block 31 that slides in a heddle guide 32 conveniently 15 formed as a trough shaped bar secured to the ring 15 by a bolt 33. The heddles 28 are reciprocated as usual by a cam drum 34 having the cam slots 35 adapted to receive shoes 36 that slide within these slots and 20 these shoes are connected to the blocks at the lower end of the heddles by pins 37. The cam drum 34 has a hub 38 that is secured to the outer portion of the cam drum by a laterally extending wall, or arms, 39. 25 The hub 38 of the cam drum is journaled upon the fixed hollow shaft 40 which is supported in an upright position at the centre of the circular loom by a hub 41. The hub 41 is supported by the lower ring 10 of 30 the frame by radially extending arms 42. A set screw 43 serves to secure the hollow shaft 40 rigidly in the hub 41. Bearing rings 44 are preferably provided near the 35 opposite ends of the rotating hub 38 and the weight of the cam drum may be supported by an anti-friction bearing 45 at the lower end of the hub 38. The cam drum 34 is shown as driven by a bevel gear 46 rigidly secured to the driving shaft 47, the 40 ends of which shaft are journaled in the bearing brackets 48. The shaft 47 is provided with the usual fast and loose pulleys 49 and 50 respectively, adapted to receive a belt passing upwardly thru the platform 12. 45 The bevel gear 46 meshes with a gear 51 formed at the lower end of the cam drum.

50 As the cam drum 34 is rotated by the means just described, the heddles 28 will be alternately raised and lowered to form a 55 shed thru which the shuttle or shuttles 52

may pass. The number of shuttles employed in a circular loom provided with the features of the present invention may be varied as desired, and it is assumed that the loom shown is provided with two shuttles 52. The 70 inner end of each shuttle 52, in the construction shown, is supported by a warp ring 53 having the warp receiving slots 54, and this ring is secured to a flange plate 55 by screws 56, which flange plate is in turn supported 75 by a fixed gear 57 the hub of which is rigidly secured to the upper end of the hollow shaft 40. The warp ring 53 is provided with a raceway upon which a shoe 58 secured to the under face of the shuttle slides. This 80 construction serves to support the inner end of each shuttle so that the shoes will pass smoothly over the slots 54 without engaging the warp threads 24 lying in these 85 slots. The shuttle 52, as is usual, is provided with a spool 59 containing the weft thread 60 that is led from the spool thru suitable tension means 61 to a guide at the inner end of the shuttle and then to the weaving point 62. A guide 63 secured to the 90 opposite sides of the shuttle frame and provided with an upper bar 64 and a lower bar 65 serves to hold the warp threads out of engagement with the shuttle.

95 In accordance with the present invention each shuttle 52 is provided at its outer end with a shoe or shoes 66 which are shown as clamped between a portion of the shuttle frame and the strip 67 secured to the shuttle frame by screws 68. These shoes are 100 positioned to slidably engage an annular bearing surface 69 formed in the inner face of the fixed drum 19. The bearing face of each shoe 66 is sufficiently wide to slide smoothly over the vertical warp receiving 105 slots 23 formed in the drum 19, and these shoes serve to take the outward centrifugal thrust of the shuttles 52 when they are operated at high speed.

110 The means of the present invention for driving each shuttle 52 consists of a disk 70 supported to travel in a circular path about the axis of the loom, and in the construction shown the disk 70 is rigidly secured to the outer end of a driving shaft 71 which shaft is journaled in a bearing bracket 72 secured to the upper face 39 of the cam drum 34. However, if it should be desired to advance the disk 70 at a different speed from that at which the cam drum 34 rotates, or if it should be desired to employ the shuttle driving means of the present invention in a loom which does not have a rotating cam drum, then some other form of driving frame that rotates about the axis of the loom may be provided to carry the disks 70. Means is provided for positively rotating each driving disk 70, and consists of a bevel gear 73 secured to the inner end of each shaft 71 and these bevel 115 120 125 130

gears mesh with the teeth 74 of the fixed gear 57. The arrangement is such that as the cam drum 34 rotates the driving disks 70 are caused to travel in a circular path about the axis of the loom, while at the same time these disks are positively rotated with the shafts 71 by the cooperating gears 73 and 74.

Each shuttle 52 is provided near its outer end, in the construction shown, with a block 75, and the lower face of each block 75 has a concave bearing surface 76 which is adapted to rest upon and partially embrace the rotating disk 70. As a result of this construction the shuttle 52 is supported and is positively driven by the disk 70 and cooperating block 75, and the shuttle is prevented from racing ahead of its driving disk when the speed of the loom is suddenly checked. Since the weight of the outer end of the shuttle is supported by the disk 70, it is unnecessary that the sliding shoes 66 support the weight of the shuttle, and, in the construction shown, the bearing surface 69 in the inner face of the drum 19 is formed as an annular slot having its lower face cut away by the inclined wall 77. The sliding shoes 66 therefore serve to take the outward thrust of the shuttle and to retain the same in place upon the driving disk 70, but preferably do not support the weight of the shuttle because if these shoes should support the weight of the shuttle, the block 75 might in some cases be prevented from resting upon its cooperating driving disk 70, which is undesirable.

Each driving disk 70 is provided with notches 78 adapted to receive the lower warp threads 23 and the disks 70 are driven at such speed that the warp threads will enter the notches 78 and will pass smoothly between the driving disks and the cooperating blocks 75 without being pinched or injured by these elements.

It is found that the sliding shoes 66 work extremely satisfactorily when they are formed of wood soaked in oil, because when they are so constructed they form self-lubricating slides and make it unnecessary to supply any lubricant to the bearing surface 69 other than supplied by the oil soaked shoes, and if the shoes become heated by friction this will serve to drive out just enough oil to lubricate the operating parts, but will not supply sufficient oil to the bearing surface 69 to cause the oil to accumulate at the slots 23 and soil the warp threads.

When the sliding shoes are made of wood it is important that the bearing surface 69 be very smooth and highly polished, in which case the wooden shoes will slide against said surface with an extremely small amount of friction.

It may also be desirable to form either the driving disk 70 or the block 75 of wood that has been treated with oil so that a self-lubri-

cating bearing surface will be provided between the disk and block which will cause the disk to rotate smoothly in the block while it supports the weight of the shuttle. If one of the cooperating elements is formed of oil treated wood then the other element should be formed of highly polished metal. For example, if the block 75 is formed of oil soaked wood then the notch disk 70 should preferably be formed of hardened steel having a highly polished peripheral surface, as the success with which a wooden bearing may be used depends largely upon the smoothness of the surface that cooperates therewith. Each shoe 66 may be secured to the shuttle by a screw 68, as shown, and the block 75 is preferably secured in a socket formed in the shuttle so that it may be retained therein by a single screw.

In the construction shown, the fabric is woven at the point 62 in the form of a tube about a flexible core 79 and the circular tube is drawn upwardly by means not shown thru the hollow mandrel 80, which mandrel may be supported at the desired height by a hub 81 secured to an arm 82 extending inwardly from the fixed drum 19. The hub 81 may serve to support a ring 83 which is held slightly above the shoe 58 of the shuttle to prevent the shuttle from moving upwardly out of engagement with the inner race-way 53.

The shuttle frame 52 is preferably provided at its inner end with a plate 84 which may be adjustably secured to the frame by screws 85 so that it may be adjusted toward and from the weaving point. At the inner end of the plate 84 is provided the guide 86 for the weft thread, and the forward edge of the plate 84 is provided with the enlarged or rounded portion 87 which helps to force the shed open.

The shed opening element 87 at the inner end of the shuttle and the guide 86 cooperate to force the shed open, and as a result it is necessary to impart only a relatively short reciprocatory movement to the heddles 28, since all they need do is to open the shed far enough to permit the rounded end of the guide 86 to enter, whereupon the guide will open the shed sufficiently to permit the shuttle to pass thru the shed. Since the construction just described requires the heddles to be moved thru only a short distance, the loom may be operated at a much higher speed than a loom employing heddles that require a long stroke.

As a result of the novel construction described each shuttle is at all times under the positive control of a driving disk 70 and cooperating block 75, and since the weight of the shuttle is supported by its driving disk and not by the sliding shoes 66, the shoes will slide freely against the annular bearing surface 69 with a minimum

of friction. Furthermore, the notches 78 in the driving disks permit the warp threads to pass between a cooperating disk and block without being pinched or frayed.

5. What is claimed is:—

1. In a circular loom, a rotating cam drum, heddles constructed to be reciprocated by the cam drum, a shuttle supported to travel in a circular path thru the shed formed by the heddles, means for driving the shuttle comprising a driving disk carried by the cam drum, and a block secured to the shuttle and having a concave bearing surface that engages the disk.
15. 2. In a circular loom, a fixed supporting frame having a shuttle race-way, means for shifting the warp threads to form the shed, a shuttle supported by said frame to travel in a circular path thru the shed, means for driving the shuttle, comprising a rotating frame, a driving disk carried by the rotating frame, and a block secured to the shuttle and having a bearing surface that engages and is driven by the disk.
20. 3. In a circular loom, a rotating cam drum, heddles constructed to be reciprocated by the cam drum, a shuttle supported to travel in a circular path thru the shed formed by the heddles, means for driving the shuttle comprising a notched driving disk rotatably mounted upon the cam drum, a block secured to the shuttle and having a bearing surface that engages the driving disk to drive the shuttle, and means for positively rotating the notched disk relatively to the bearing block to promote the passage of warp threads between the disk and block.
25. 4. In a circular loom, a fixed drum having an annular bearing surface formed at its inner face, a rotating cam drum, heddles constructed to be reciprocated by the cam drum, a shuttle supported to travel within said fixed drum thru the shed formed by the heddles, means for driving the shuttle comprising a driving disk carried by the cam drum, a block secured to the shuttle and having a concave bearing surface that engages the disk, and thrust means extending from the shuttle into engagement with said bearing surface.
30. 5. In a circular loom, a rotating cam drum, heddles constructed to be reciprocated by the cam drum, a shuttle supported to travel in a circular path thru the shed formed by the heddles, means for driving the shuttle comprising a driving disk mounted to travel about the axis of the loom, and a block secured to the shuttle and having a concave bearing surface which the disk engages to drive the shuttle.
35. 6. In a circular loom, a fixed drum thru which the warp threads extend, means for shifting the warp threads to form the shed, a shuttle supported, within the drum to

travel in a circular path thru the shed, means for driving the shuttle, comprising a rotating frame, a driving disk carried by the rotating frame, and a block secured to the shuttle and having a bearing surface that rests upon the driving disk to support and drive the shuttle.

7. In a circular loom, a fixed drum having a shuttle race-way, means for shifting the warp threads to form a shed thru which the shuttle may pass, a shuttle supported to travel in a circular path thru the shed, means for driving the shuttle comprising a rotating frame, a notched driving disk carried by the rotating frame, a block secured to the shuttle and having a bearing surface that engages the driving disk to drive the shuttle, and means for positively rotating the notched disk relatively to the bearing block to promote the passage of warp threads between the disk and block.

8. In a circular loom, a fixed drum having an annular bearing surface facing the axis of the loom, a rotating cam drum, heddles constructed to be reciprocated by the cam drum, a shuttle supported to travel within the fixed drum thru the shed formed by the heddles, means for driving the shuttle, and spaced shoes disposed at the opposite sides of a vertical plane passing centrally thru the shuttle and the loom axis and extending horizontally in the same plane from the outer end of the shuttle into sliding engagement with said bearing surface to take the outward centrifugal thrust of the traveling shuttle.

9. In a circular loom, a fixed drum having an annular bearing surface, means for shifting the warp threads to form a shea thru which the shuttle may pass, a shuttle supported to travel in a circular path thru the shed, means for driving the shuttle, and spaced shoes disposed at the opposite sides of a vertical plane passing centrally thru the shuttle and the loom axis and extending from the outer end of the shuttle in the same horizontal central plane to slidably engage said annular bearing surface and take the centrifugal thrust of the traveling shuttle.

10. In a circular loom, a fixed drum having an annular bearing surface, means for shifting the warp threads to form a shed thru which the shuttle may pass, a shuttle mounted to travel in a circular path thru the shed, means for driving the shuttle, comprising a disk that is supported to travel in a circular path about the axis of the loom, a block upon the shuttle and having a bearing surface that rests upon the driving disk to support and drive the shuttle, and a shoe extending from the outer end of the shuttle into sliding engagement with the annular bearing surface and constructed to take the outward centrifugal

thrust of the shuttle without supporting the weight of the shuttle.

11. In a circular loom, a fixed drum having an annular bearing surface, means for shifting the warp threads to form a shed thru which the shuttle may pass, a shuttle supported to travel in a circular path thru the shed, means for driving the shuttle, and a shoe formed of wood and extending from the outer end of the shuttle in the central horizontal plane of the shuttle into sliding engagement with said annular bearing surface to take the centrifugal thrust of the traveling shuttle.

12. In a circular loom, a fixed drum having an annular bearing surface facing the axis of the loom, heddles supported for reciprocatory movement, means for operating the heddles to form the shed, a shuttle supported to travel within the fixed drum thru the shed, means for driving the shuttle, and a shoe formed of oil soaked wood extending from the shuttle into sliding engagement with said annular bearing surface and forming a self-lubricating slide.

13. In a circular loom, a fixed drum having an annular bearing surface, a shuttle supported to travel within the fixed drum, means for shifting the warp threads to form a shed thru which the shuttle passes, a race-way for supporting the inner end of the shuttle, a shoe upon the shuttle for slidably engaging said annular bearing surface, a second shoe upon the shuttle for slidably engaging said race-way, one of said shoes being formed of wood treated with oil to form a self-lubricating slide, and means for driving the shuttle.

14. In a circular loom, a fixed drum having an annular bearing surface, means for shifting the warp threads to form the shed, a shuttle supported within the drum to travel in a circular path thru the shed, and a shoe means for driving the shuttle, and a shoe formed of oil-treated wood extending from the shuttle into sliding engagement with said annular bearing surface and forming a self-lubricating slide.

15. In a circular loom, a fixed drum having an annular bearing surface, a rotating driving frame, a shuttle mounted to travel in a circular path about the axis of the

loom, means for shifting the warp threads to form a shed thru which the shuttle may pass, means for driving the shuttle, comprising a disk that is mounted upon said driving frame to travel in a circular path about the axis of the loom, a block secured to the shuttle and having a bearing surface that rests upon the driving disk to support and drive the shuttle, and means extending from the shuttle into engagement with said annular bearing surface to retain the shuttle in place upon the driving disk.

16. In a circular loom, a rotating cam drum, heddles constructed to be reciprocated by the cam drum, a shuttle supported to travel in a circular path thru the shed formed by the heddles, means for driving the shuttle comprising a driving disk carried by the cam drum, a block secured to the shuttle and having a concave bearing surface that engages the disk, and means for positively rotating the disk to promote the passage of the warp threads between the disk and block, including a gear secured to the disk and a fixed ring gear with which said gear meshes to cause the gear to rotate as it travels about the axis of the loom.

17. In a circular loom, a fixed supporting frame having a shuttle race-way, means for shifting the warp threads to form the shed, a shuttle supported by the frame to travel in a circular path thru the shed, means for driving the shuttle, comprising a rotating frame, a driving disk carried by the rotating frame, and an oil treated wooden block secured to the shuttle and having a bearing surface that is engaged and driven by the disk.

18. In a circular loom, a fixed supporting frame having a shuttle race-way, means for shifting the warp threads to form the shed, a shuttle supported by the frame to travel in a circular path thru the shed, means for driving the shuttle, comprising a rotating frame, a driving disk carried by the rotating frame and a cooperating block secured to the shuttle and one of them being formed of oil treated wood to provide a self-lubricating bearing between the disk and block.

In testimony whereof, I have signed my name to this specification.

OTTO A. FREDERICKSON.
